E. F. MARTINET

SUCTION CLEANING APPARATUS

Filed June 15, 1927

UNITED STATES PATENT OFFICE.

EUGENE F. MARTINET, OF CLEVELAND, OHIO, ASSIGNOR TO THE P. A. GEIER COMPANY, OF CLEVELAND, OHIO, A CORPORATION OF OHIO.

SUCTION CLEANING APPARATUS.

Application filed June 15, 1927. Serial No. 198,958.

My invention relates to improvements in suction cleaning apparatus, and, more particularly, to an adjustable brush attachment for suction cleaning nozzles adapted to be actuated and locked in a plurality of operative and inoperative positions with respect to said nozzle. My invention has for its object the provision of a brush attachment which may readily be actuated conveniently, 10 as by the foot of the user, so that the different requirements of suction cleaning may adequately be met.

In U. S. Letters Patent to Robertson, No. 1,382,548, June 21, 1921, there is shown and 15 described a retractile brush member positioned rearwardly of a suction cleaner nozzle, which is adapted to be actuated into spring-pressed floating relation with respect to the surface that is being cleaned, but the 20 brush does not operate forwardly of the nozzle, nor is it capable of being rigidly locked in its extended operative position, as required for certain classes of combined brushing and suction cleaning.

25 My present improvement contemplates novel features, comprising a brush member having front and rear sections equipped with means for actuating it into three distinct operative and inoperative positions with respect to the nozzle upon which it is mounted. The actuating means are of the simplest, directly-acting construction and preferably permit of their actuation by the foot of the user, so that no stooping is necessary and the 30 brush member may be shifted almost instantly from one position to another, depending upon the nature of the work to be done.

It has been found in practice that while the floating relation of the brush above referred to more commonly is required for 40 cleaning rugs and floor coverings, frequently a lighter brushing action is more effective at front and back of the nozzle for certain classes of litter, while a rigidly attached and 45 fully extended brush member is demanded for heavier cleaning operations, and particularly for cleaning adjacent bare floors bordering the rugs, without readjustment of the working height of the suction cleaner nozzle.

50 The foregoing requirements all are admirably met by my improved construction, embodying a freely floating brush, and one that may be positively locked in fully extended and retracted position, the details of which, and typical operation thereof, may

best be explained in connection with the accompanying drawings wherein:

Figure 1 is a view of a suction cleaner nozzle equipped with my improvements, the brush being locked in its fully retracted position with the bristles flush or slightly elevated above the mouth of the nozzle, 60

Fig. 2 is a similar view thereof illustrating by full and dotted lines the free floating position of the brush, 65

Fig. 3 is another similar view illustrating the fully extended, locked position of the brush, 70

Fig. 4 is a median sectional view on line 4-4, Fig. 1, 75

Fig. 5 is a fragmentary end view partially broken away,

Fig. 6 is an end elevation of the nozzle and brush adjustment of Fig. 2, partially broken away and in section, and 75

Fig. 7 is a similar view of the nozzle and brush adjustment of Fig. 3.

Throughout the several figures of the drawings I have employed the same character of reference to indicate similar parts. 80

Figure 1 illustrates a detachable nozzle member *a* of well known construction, and one adapted to be attached to a portable suction cleaner of the type disclosed in the Robertson patent supra, for example. An 85 enclosing brush member *b*, having rows of bristles *b'* and *b''*, respectively at the front and back of said nozzle, and terminal rubber protectors *b*³, is afforded a range of adjustment with respect to the nozzle opening by means of the slotted support *c* carried by the post *c'* and screw *c''* rearwardly of the nozzle member and practically concealed thereby when the device is in position for use. 95

Two substantially square bracket members *d*, together with the rotatable rod *e*, terminally looped at *e'* to engage said bracket members and the retaining spring or resilient detent *d'*, respectively co-operate to adjust the brush member. The rod *e* is pivoted to rotate within the perforated rectangular lugs screwed rearwardly of nozzle *a* so that the ends *e'* may be rotated through an arc approximately of 180°. When the looped 105 ends *e'* are in their uppermost position, as shown in Figs. 1, 4 and 5, it will be seen that the brush is locked in its fully retracted and inoperative position by resilient detent *d'*, thus permitting air-cleaning operations 110

alone with the use of the nozzle and suitable associated suction apparatus, not necessary to be shown.

At the extreme left of the rotatable rod *e* 5 and engaging the looped end *e'*, there is provided an actuating member *f*, having the angularly bent lugs *f'*, *f''* adapted primarily to be actuated by the foot of the user for the purpose of turning the rod *e* from one position to another, in order to effect the shifting of the brush from one into any other of its inoperative or operative positions. Thus, in Figs. 2 and 6 the looped ends *e'* are in rectangular relation with the brush 10 and nozzle, so that the brush member is free to float from the operative to substantially the inoperative position thereof, guided by the slotted support *c* and the square brackets *d*. This insures a light 15 brushing action for the rugs or carpets in order to dislodge the dust, and one that involves practically no wear of the floor covering.

However, in order to afford means for 20 brushing the adjacent bare floor or for dislodging caked and embedded dirt, the user will press the upper lug *f'* to substantially its rectangular position of Figs. 3 and 7, with a corresponding actuation of the rod *e* 25 and its ends *e'*. Thus the brush member will be locked in its fully extended position, affording rigid brushing attachments at the front and rear of the nozzle for heavy cleaning duty, in association with the air currents 30 normally drawn through the nozzle. The adjacent bare floor bordering the edges of the rug may thus be thoroughly cleaned without readjusting the height of the nozzle mouth with respect to the floor, while a 35 sweeping action both at the front and rear of the nozzle is efficiently provided. The change from one position to any other may be instantly made.

From the foregoing, it will be seen that 40 a very cheap and simple mechanism interposed between the brush member and nozzle, and one capable of being operated by the foot of the user, affords three separate positions for the enclosing brush member with 45 respect to the nozzle.

Having now described apparatus embodying my invention in its preferred form and the utility thereof when associated with suitable suction cleaning apparatus, I claim as 50 new and desire to secure by Letters Patent, the following:

1. The combination with a suction cleaning nozzle, of a brush member vertically adjustable with respect to the mouth of said nozzle and operatively associated therewith, a horizontally positioned rotatable adjusting member interposed between said brush and nozzle, detent means for maintaining the brush in adjusted position, and an actu-

ating lever provided on said adjusting member having a plurality of angularly positioned members adapted to be alternatively engaged by the foot of the user, substantially as set forth. 65

2. The combination with a suction cleaning nozzle, of a brush member mounted upon the nozzle and vertically adjustable with respect to the mouth of said nozzle and enclosing it at front and rear, a slide-support for the brush member, provided upon the nozzle, means interposed between the brush member and the nozzle for insuring its locking in operative and inoperative positions or in floating relation with respect to the nozzle mouth, alternatively, and a detent for maintaining the parts in their temporarily adjusted position, substantially as set forth. 70

3. The combination with a suction cleaning nozzle, of a vertically movable brush member adjustably mounted thereon adjacent to the mouth, a horizontal rotatable rod having actuating parts extending outwardly from its axis, brackets positioned upon the brush member engaging said actuating parts only in their diametrical rotated positions, and a detent upon the nozzle adapted to maintain the actuating parts temporarily in adjusted position, substantially as set forth. 75

4. The combination with a suction cleaning nozzle, of a brush member mounted upon the nozzle and vertically adjustable at the front and rear of the nozzle mouth, a slide support therefor provided upon the nozzle, a horizontal rotatable rod having actuating parts extending outwardly from its axis, brackets interposed between said rod and brush member engaged by the actuating parts in a plurality of operative positions and released in an intermediate position, and a detent upon the nozzle adapted to maintain the actuating parts temporarily in any of their adjusted positions, substantially as set forth. 80

5. The combination with a suction cleaning nozzle, of a brush member mounted upon the nozzle and vertically adjustable with respect to the nozzle mouth, a slide support therefor provided upon the nozzle, a horizontal rotatable rod having its ends bent at an angle to afford actuating parts, bracket members upon the brush engaging said ends to afford three positions of adjustment therefor, whereby the brush may be rendered operative or inoperative or in floating relation with respect to the nozzle, and a detent upon the nozzle adapted to maintain the brush members temporarily in any of the three adjusted positions, substantially as set forth. 85

In testimony whereof I do now affix my 90 signature.

EUGENE F. MARTINET.
